United States Patent Office

Des. 202,328
Patented Sept. 21, 1965

202,328

DRAFT ARM, OR SIMILAR ARTICLE

James R. Reichow, Edina, Minn., assignor to The
Cornelius Company, Anoka, Minn., a corporation
of Minnesota

Filed Oct. 13, 1964, Ser. No. 82,154

Term of patent 14 years

(Cl. D2—3)

FIG. 1

FIG. 2

FIG. 3FIG. 4FIG. 5FIG. 1 is a front elevational view of a draft arm, showing my new design.

FIG. 2 is a side elevational view thereof, the opposite side having a reverse appearance.

FIG. 3 is a rear elevational view thereof.

FIG. 4 is a top plan view thereof.

FIG. 5 is a cross-sectional view thereof taken along line V-V of FIG. 3.

The dominant features of my design reside in the full lines portion.

I claim:

The ornamental design for a draft arm, or similar article, substantially as shown and described.
